(57) CLAIM

The ornamental design for a decorative cover for a pull out wand handle, as shown and described.

DESCRIPTION

FIG. 1 is a perspective view of a decorative cover for a pull out wand handle, showing my new design;

FIG. 2 is a top view of the decorative cover;

FIG. 3 is a side view of the decorative cover;

FIG. 4 is a perspective view of the decorative cover, showing the decorative cover positioned in a pull out wand handle;

FIG. 5 is a top view of the decorative cover positioned in a pull out wand handle;

FIG. 6 is a side view of the decorative cover positioned in a pull out wand handle; and,

FIG. 7 is an end view the decorative cover positioned in a pull out wand handle.

The bottom of the decorative cover, not shown, is substantially unadorned.

The broken lines in FIGS. 4, 5, 6, and 7 are for illustrative purposes only and forms no part of the claimed design.

1 Claim, 3 Drawing Sheets
